ROTARY DENTAL BRUSH

Edward Owen Coggeshall, Shirley, Mass.

Application August 29, 1955, Serial No. 530,958

2 Claims. (Cl. 15—179)

This invention relates to a brush arrangement for polishing dental appliances, such as bridge work and the like, and, more particularly, it is directed to a rotary brush in which rotary and reciprocatory components of motion are imparted to the bristles at the point of contact with the surface being polished.

The brushes used by the dental technician in polishing normally consist of a disc-like hub having a cylindrical hole formed at the axis thereof and having an annular row of bristles around the periphery of the disc. Polishing is effected by rotating the brush about its axis at high speed and engaging the bristles with the surface to be polished. Two principal disadvantages attend the polishing operation with such known brushes. The first is that the annular ring of bristles tends to form undesirable grooves in the surface of the workpiece. The second disadvantage is that the commonly used brush tends to throw a large portion of the pumice used in the operation.

The present invention is designed to overcome the disadvantages of the prior art. The essence of the invention is to provide means for imparting a reciprocatory component of motion to the normal rotary motion at the point of contact with the workpiece. The added component of motion has a tendency to minimize the throwing of pumice and substantially avoids the problem of cutting grooves into the polished surface.

Several forms will be described in detail below. Each has a principal advantage over the others, and all have the common denominator of combining the two components of polishing motion. In the preferred embodiment, the annular ring of bristles lies in a plane inclined to the plane normal to the axis of hub rotation. Rotation of the hub about its axis therefore necessarily imparts a reciprocatory component of motion to the bristles at the point of contact with the workpiece.

In the second and third forms, a standard brush is used, and each is provided with a ball and socket connection between the brush and the driving mechanism, so that the brush may be set at an angle to the axis of rotation. In the first of these two embodiments, the socket is formed in the hub of the brush and the driven chuck has a ball engageable with that socket. In the second of the last two embodiments, a standard hub is used with the standard arbor chuck, except for the fact that the end of the arbor chuck is formed with a ball which engages the socket member.

The last form has the advantage that the standard chuck can be used, thus permitting a rapid interchange between the brush, on the one hand, and the other tools normally used by the dental technician.

It is a principal object of the invention to provide a dental polishing brush having means for imparting a combined reciprocatory and rotating component of motion to the bristles of the brush at the point of contact with the workpiece.

Other objects of the invention will become more readily apparent from a consideration of the following

detailed description of the invention taken in conjunction with the accompanying drawings, in which:

Fig. 1 is a plan view of the rotary brush constructed according to the invention;

5 Fig. 2 is an exploded view in elevation, showing the brush and the arbor chuck;

Fig. 3 is a plan view of an alternative embodiment;

Fig. 4 is an exploded view of the alternative embodiment;

10 Fig. 5 is a sectional view through the center of the brush in the alternative embodiment;

Fig. 6 is an exploded view of a second alternative embodiment; and

Fig. 7 is an elevational view of the second embodiment

15 in assembled condition.

The preferred embodiment of the invention is shown in Figs. 1 and 2. The rotary brush consists of a cylindrical supporting member or hub 10 which is rotatable about its axis and into which bristles 12, of equal length

20 and generally perpendicular to the axis of rotation, are set in any suitable, known manner. Formed in the supporting member 10 is an arbor receiving hole 14 formed by two frusto-conical surfaces 16.

One of the essential features of this embodiment is

25 shown best in Fig. 2. In this figure, it will be observed that the bristles lie in a plane which is inclined at an angle to the plane normal to the axis of the supporting member. Thus when the brush is rotated at high speed

around its axis, with the bristles engaging a surface to be polished, the bristles have a reciprocating component of motion at the point of contact with the workpiece. This reciprocating component of motion tends to avoid

grooving of the surface being polished and minimizes the spraying of the pumice during the polishing operation.

30 Further, a larger surface area is covered, thus speeding the polishing operation.

Fig. 2 also demonstrates another aspect of the invention, namely, the manner in which the brush cooperates with an arbor chuck 18. The arbor chuck 18 has a

35 tapered screw-threaded portion 20 which is standard for engagement with most of the tools of the dental technician.

The frusto-conical surfaces 16 of the bristle-supporting member 10 have a taper designed for receiving a standard tapered arbor chuck, as shown, in screw-threaded engagement.

40 This arrangement permits a large number of threads in the chuck and hole to be mutually engaged, thus holding the brush hub steady during the polishing operation.

A second embodiment is shown in Figs. 3, 4 and 5.

50 In this embodiment, bristles 22 are mounted on a supporting member or hub 24 in the standard manner with the plane of the bristles lying in a plane normal to the axis of the supporting member. The supporting member, however, is formed with a generally semi-spherical recess

55 26, which cooperates with a specially designed chuck 28.

The chuck 28 has a shank 30 which cooperates in the usual manner with means for rotating the chuck. The hub-receiving end of the chuck is formed with an oblate spheroid member 32 formed of rubber or other similar

60 material having the characteristics of resilience and a high friction surface. The member 32 is fixed to the shank 30 by a bolt 34 and washer 36, the bolt 34 being threaded into the suitable recess 38 formed in the shank of the chuck. The shank has an annular flange 40 which

65 engages the side of the spheroid member 32 remote from the washer 36.

The size of the member 32 is such that it will fit snugly in the semi-spherical recess 26 of supporting member 24, and can be firmly retained in that recess by tightening

70 down bolt 34, which tends to compress the spheroid member 32, expanding its peripheral surface against the surface of recess 26.

The manner in which the device is used is best shown in Fig. 5. That figure demonstrates that the plane of the bristles can be inclined to any suitable angle by properly positioning the supporting member 24 with respect to the chuck 23 prior to the tightening of bolt 34.

The device of Figs. 3 to 5 has the disadvantage of lack of convenience in the technician's normal operation. In such operation, the technician finds it convenient to use a standard arbor chuck to which so many of his operating tools are attachable. The embodiment of Figs. 6 and 7 show how the advantages of the brush having the reciprocatory component of motion can be combined with the standard arbor chuck without necessitating the use of a specially designed brush.

In this embodiment, the arbor chuck having the standard tapered portion 44 is provided at one end thereof with a ball-shaped shank 46. Cooperating with the shank 46 is a bifurcated socket member 48 which is threaded along a major portion of its length at 50. A nut 52 cooperates with a thread 50 so that when the nut 52 is turned down toward the socket portion 48, the two portions of the socket member clamp down on the ball 46.

The remaining part of the socket shank is shown as it appears before being fixed to a member 54, by which the device is attached to the driving arrangement. Advantageously, after the nut 52 is threaded onto the portion 50, the portion 50 can be welded to the member 54.

It will be apparent that the arbor chuck may be set at any angle, within a wide range, to the axis of rotation of the driven member 54. Thus reciprocatory components of varying amounts of motion can be applied to a standard brush attached to the end of the chuck. The undesirable vibration accompanying the use of this embodiment of the invention is compensated for by the adaptability of the arbor to a large number of the other tools normally used by the dental technician.

In a general manner, while there has been disclosed in the above description what is deemed to be the most practical and efficient embodiment of the invention, it

should be well understood that the invention is not limited to such embodiment, as there might be changes made in the arrangement, disposition and form of the parts without departing from the principle of the present invention, as comprehended within the scope of the accompanying claims.

I claim:

1. A rotary brush comprising a cylindrical hub rotatable about its axis, a row of bristles mounted in said hub around the cylindrical surface thereof, said bristles being of substantially equal length and individually extending generally perpendicular to said axis all around the periphery of said hub, said row of bristles having adjacent increments thereof offset with respect to each other along said axis to provide a generally circular endless periphery lying in a plane inclined to said axis, the projection of said brush in the direction of said axis being circular.

2. A rotary brush comprising a cylindrical hub rotatable about its axis, a row of bristles mounted in said hub around the cylindrical surface thereof, said bristles being of substantially equal length and individually extending generally perpendicular to said axis all around the periphery of said hub, said row of bristles providing a generally circular endless periphery lying in a plane inclined to said axis, the projection of said brush in the direction of said axis being circular.
